**NONSTRIP CONNECTOR FOR INSULATED
ELECTRICAL CONDUCTORS AND ELECTRICAL
CONDUCTORS THEREFOR**

This invention relates to solderless connectors and more specifically to crimped-type connectors in which a compression ring channel or sleeve-like connector is crimped onto an insulated wire to force a piercing member through insulation to make an electrical contact with the conductor of the insulated wire. This invention further relates to the specific insulated wire used in these type of channel or sleeve-type connectors. This invention is a further development of my U.S. Pat. No. 3,390,227 issued June 25, 1968, and Marley et al. U.S. Pat. No. 3,320,354 issued May 16, 1967.

GENERAL SUMMARY

In general, this invention relates to a connector which is provided with an area for initially receiving an insulated electrical conductor prior to crimp and a second area for receiving the electrical conductor upon crimping operation. The crimping operation being one which eliminates the first-mentioned area. The invention also involves a specific conductor having a slot having its vertical axis intersecting the electrical conductor but in which the slot ends short of the electrical conductor prior to crimp.

HISTORICAL BACKGROUND AND OBJECTS

The patents referred to above being earlier developments in general were more complex, requiring more elaborate manufacturing techniques, more parts, and thus a greater expense. The connectors of the patents utilized standard insulated wire which as will be shown is possible with this invention; nevertheless, by using a specifically designed insulated wire, a more effective and more reliable connection is provided.

It is therefore an object of this invention to provide a connector which is inexpensive to manufacture, has a minimum number of parts, and is easily assembled.

The further object of this invention is to provide an electrical connector which when crimped will provide a waterproof connection for use in damp and wet areas.

Still a further object of this invention is to provide a connector in which a plurality of leads are electrically connected simultaneously.

Yet a further object of this invention is to provide a solderless connector which may be installed easily by means of a hand tool.

Another object of this invention is to provide a connector which will maintain a good positive contact at all times under a great variation of physical conditions.

Yet a further object of this invention is to provide a connector for insulated leads which requires a minimum of space.

Still another object of this invention is to provide a sealable connector which maintains a positive connection at all times and which will not be readily removed upon tension being applied to the wire.

A further object of this invention is to provide a connector for wires which require a minimum of installation time and a maximum of operating efficiency.

Another object of this invention is to provide an insulated electrical conductor which is specifically designed for use with this connector.

Yet a further object of this invention is to provide an electrical connector which may use either a standard electrical insulated conductor or a specifically designed insulated conductor.

These and other objects of this invention will be apparent from the following description and claims. In the accompanying drawings which illustrate by way of example various embodiments of this invention:

FIG. 1 is a perspective view of the connector;

FIG. 2 is a cross-sectional view taken along the lines 2-2 of FIG. 1 and viewed in a direction of the arrows;

FIG. 3 is an enlarged fragmentary cross-sectional view taken along the line 3-3 of FIG. 2 and viewed in the direction of the arrows;

FIG. 4 is an end view of the connector with the insulated conductor inserted therein and the assembly mounted in a crimping tool prior to crimp;

FIG. 5 is the assembly of FIG. 4 mounted in the crimping tool subsequent to crimp;

FIG. 6 is an end view showing a further embodiment of this invention with the insulated conductors inserted therein;

FIG. 7 is still a further embodiment of this invention showing the insulated conductors inserted and the assembly mounted in a crimping tool prior to crimp;

FIG. 8 is an end view showing still a further modification of this invention with the insulated conductors inserted and the assembly mounted for crimp in a crimping tool;

FIG. 9 is a fragmentary perspective view of still a further connector embodiment with the insulated conductors removed;

FIG. 10 is a further embodiment showing an end view of the connector with special electrical conductor adapted specifically for the connector and inserted therein and the assembly mounted in a crimping tool prior to crimp operation;

FIGS. 11 and 12 illustrate yet another embodiment of this invention with the electrical conductors mounted in the connector and the assembly mounted within a crimping tool showing the assembly prior to crimp and subsequent to crimp respectively;

FIGS. 13 thru 17 respectively, are cross-sectional views of the insulated conductors available for use in the connectors such as illustrated in FIGS. 8 thru 12 respectively;

FIG. 18 is a perspective view illustrating yet a further embodiment of this invention with the insulated conductors inserted therein and prior to crimp;

FIG. 19 shows the embodiment of FIG. 18 mounted in a crimping tool and subsequent to crimp;

FIG. 20 is a perspective view showing a further embodiment of the invention;

FIG. 21 is a cross-sectional view showing the connector of FIG. 20 with the insulated conductors positioned therein subsequent to crimp and the assembly mounted in a crimping tool;

FIG. 22 is a perspective view illustrating another embodiment of the invention;

FIGS. 23 and 24 show the embodiment of FIG. 22 with the electrical conductors positioned in a crimping tool prior to and subsequent to crimp operation respectively;

FIG. 25 is a perspective view of still another embodiment of this invention;

FIG. 26 is an end view of the connector illustrated in FIG. 25 with conductors inserted and the assembly mounted in a tool prior to crimp;

FIGS. 27 and 28 illustrate an end view of still a further embodiment of this invention with insulators positioned within the connector and the assembly mounted in a crimping tool prior and subsequent to crimp respectively;

FIGS. 29 and 30 show end views of a further embodiment of this invention showing the insulated conductors positioned in the connector and the assembly mounted in a crimping tool prior and subsequent to crimp respectively;

FIG. 31 is an end view illustrating the further modification of this invention with an insulated conductor inserted therein;

FIG. 32 is a perspective view of the connector illustrated in FIG. 31 subsequent to crimp;

FIG. 33 is a perspective view with portions illustrated in dash lines of yet a further embodiment of this invention illustrating the connector and a specific insulated conductor used therein;

FIG. 34 is a perspective view illustrating the embodiment of FIG. 3 subsequent to crimp;

FIG. 35 is a perspective view with portions broken away illustrating yet a further embodiment of this invention with a specifically designed insulated conductor used therein;

FIG. 36 is a cross-sectional view prior to crimp showing yet another embodiment of this invention including a specially designed insulated conductor for use in the connector;

FIG. 37 illustrates yet another insulated conductor available for use in the connector illustrated in FIG. 36;

FIG. 38 illustrates yet a further embodiment of the electrical connector of this invention;

FIG. 39 illustrates yet a further embodiment of the electrical connector of this invention utilizing a crimp ring;

FIG. 40 is a cross-sectional view of yet a further embodiment of a connector of this invention utilizing a crimp ring;

FIG. 41 is a cross-sectional view taken along the line 41—41 in FIG. 40 and viewed in the direction of the arrow.

FIGURES 1 THRU 7

In FIG. 1, the connector C includes a sleeve housing 2 of a D-shaped configuration. The base portion 4 of the housing 2 is flat and has struck up therefrom a series of insulation piercing members 6 resulting in strikeouts 8. The housing 2 may be constructed from tubing or from flat sheet stock which forms a seam 10. The housing 2 may be of metal and may be coated with a sealing insulation coat 12. Additional sealant 14 as best illustrated in FIG. 3 is provided so that when the connector C is crimped the sealant will flow in order to provide a waterproof seal around the conductors which are inserted into the connector C.

In FIG. 4, an insulated conductor 16 provided with insulation 18 is inserted into the upper area portion of the central cavity 20. The insulation piercing members 6 are spaced apart a distance less than the width of the insulated conductor 16. The assembly is then placed into the female member 22 of the crimping tool T. The male member 24 is then brought down against the connector C which is held by the female member 22 and crimped. The crimping operation drives the insulation piercing members 6 up through the insulation 18 and in contact with the insulated conductor 16. If the connector C has been coated with a sealing insulation coat 12 as illustrated in FIG. 3 including the piercing members 6, the sealing insulation coat 12 will be stripped from the insulation piercing members 6 because of the engagement with insulated conductors 16 thus forming a positive electrical connection as best illustrated in FIG. 5. The additional sealant 14 will flow about any of the areas which have been stripped in order to form a positive seal against water etc. It will be observed that the crimping action as illustrated in FIG. 5 will force the insulated conductor from the upper portion of the central cavity 20 into the lower area portion and in effect eliminate the upper area portion entirely.

In FIG. 6, the housing 26 is modified slightly so as to provide abutting flanges 28. It will be noted that the housing 26 has four transversally positioned insulation piercing members 6 for connecting side by side insulated conductors 16.

FIG. 7 shows a slight modification of FIG. 6 in which a central insulation piercing member 30 is provided between two outer insulation piercing members 6. In this instance, no seam 10 or abutting flanges 28 are provided and the housing 2 is manufactured from tubular stock. It is to be noted that the tool T including the female die member 22 has a male die member 32 having a slightly different configuration than that illustrated in FIGS. 4 and 5.

FIGURES 8 THRU 17

In FIG. 8, the connector C is provided with a housing 34 which has an outside rectangular configuration and the X-shape to the central cavity 36. Insulation piercing means 38 oppose each other and their vertical axes intersect the insulated conductors 16. The V-shaped supporting areas 40 maintain proper alignment of the insulated conductors 16 and prevent excessive distortion of the insulation 18 thereon. Female die 22 supports the conductor C in FIG. 8 and the male die 42 crimps the housing 34 to force the insulation piercing means 38 down through the insulation 18 and into en-

gagement with the insulated conductors 16. If the housing 34 is of plastic, an internal coating of conductive material would be applied at least to the insulation piercing means 38 and possibly between the upper and lower insulation piercing means for connection therebetween as desired.

FIG. 9 shows a connector C with a central cavity 44 having an X-configuration slightly different than that illustrated in FIG. 8.

In FIGS. 11 and 12, the connector C is provided with a 10 housing 46 having a configuration resembling a pair of E's in face-to-face relationship and connected by an inverted V-connection. The central leg 50 of the E's includes the pin insulation piercing means. It will be noted that the upper legs 52 are spaced apart from each other a distance which permits the insertion of an insulated conductor 16. FIG. 12 shows how the central legs 50 pierce the insulation and contact the insulated conductor 16 to form an electrical circuit. It will be further noted that the legs 52 as well as the inverted V-connection have moved closer together after crimping operation. It will be obvious that this connector C as well as any of the other connectors referred to heretofore or hereafter referred to can include the sealing insulation coat 12 and the additional sealant material 14.

FIG. 13 shows a D-shaped insulated conductor 54 having a slot 56 therein. The insulated conductor 54 may be used as for example in the connectors C illustrated in FIGS. 7, 8 and 11.

FIG. 14 shows an X-shaped configuration for an electrical conductor 58 having two conducting wires 60 in line with the 30 V slots 62. It is to be noted that portions of the X-shaped conductor have curved surfaces 64.

FIG. 15 shows an X-shaped conductor 66 having a conductor wire 68 and FIG. 16 shows an X-shaped conductor 70 having a pair of conductor wires 72. The X-shaped conductors 58, 35 66 and 70 may be utilized as for example in FIGS. 7 and 8.

FIG. 17 shows a rectangular conductor 74 having slots 76. A single-conductor wire 78 is illustrated in FIG. 17. The conductor 74 may be used for example in the conductor C illustrated in FIG. 10 having a rectangular housing 80 with a pair 40 of lancing or insulation piercing members 82. FIG. 10 illustrates a slightly different modification of the conductor 74 in that it is provided with a pair of conductor wires 84.

FIGURES 18 AND 19

In FIGS. 18 and 19, the connector C is provided with a 45 housing 86 which resembles a written small "t." The insulation piercing means 88 projects downwardly from the crossbar of the "t." It will be noted as in FIG. 19, that the furcations 90 of the bifurcated leg 92 close up against the crossbar of the housing 86.

It will be further noted that the male and female dies 94 and 96 respectively are slightly modified in configuration in order to permit positive forming of the connector during crimping 55 operation.

FIGURES 20 AND 21

FIG. 20 shows a modified housing 98 which has an E-shaped 60 configuration. It is to be noted that the center leg 100 of the E in FIG. 13 extends substantially above the outer legs 102. The insulation piercing means 104 have been struck outwardly from the center leg 100. It will be noted in FIG. 21 that upon crimping, the outer legs 102 become longer than the center leg 100 and the center leg no longer projects above the outer legs 102. It is also to be noted that the male die member 106 has a slightly different configuration than other male die members heretofore described to permit positive action particularly on the center leg 100 which fits into a notch 108 in the male die 106.

FIGURES 22 THRU 26

In FIG. 22, the connector C comprises a housing 110 which 70 is of C-shaped configuration. Insulation piercing means 112 are provided which are struck out from the center portion of

the housing 110. It should also be noted that the male die member 114 and the female die member 116 have been somewhat modified to provide for crimping action as illustrated in FIGS. 23 and 24.

The connector C illustrated in FIGS. 25 and 26 is provided with a housing 118 which resembles a pair of C's in back-to-back relationship. The housing 118 may be extruded or may be formed from two housings such as 110 connected in back-to-back relationship by welding or the like. The male die member 120 and the female die member 122 are shown modified in FIG. 26 to provide proper crimp action.

FIGURES 27 AND 28

In FIGS. 27 and 28, the conductor C has an E-shaped housing 124. The outer legs 126 of the E are substantially longer than the central leg 128 when in noncrimped position. The ends 130 of the outer legs 126 provide the piercing means and are doubled back and aligned with the insulated conductors 16.

It will be noted in FIG. 28 that upon crimping, the central leg 128 becomes longer and may project up into the recess 132 of the specially designed male die member 134 of the crimping tool. Female member 122 in FIG. 26 may be utilized for the operation illustrated in FIGS. 20 and 21. It is to be noted that the male member 134 has curved areas 136 for controlling the outer legs of the E-shaped housing 124.

FIGURES 29 AND 30

FIGS. 29 and 30 show a connector C having an outer rectangular configuration and having an inner central cavity provided with three in line downwardly projecting members. The inner member 138 is a dividing member and the outer members 140 are the insulation piercing members. FIG. 29 illustrates how the piercing members 140 penetrate the insulation and how the central member 138 tends to keep the connectors positioned in proper relationship so that the conductors 16 will be in line with the piercing points of the members 140. FIGURES 31 AND 32

In FIGS. 31 and 32, the conductor C is provided with a D-shaped housing 142 having an insulation piercing means 144. The housing may be uniform throughout its length or may be as illustrated in FIG. 32 in which the flat portion 146 serves as a strap connecting the end portions 148.

Merely crimping the end portions as illustrated in FIG. 32 provides connection between the two insulated conductors 16.

FIGURES 33 AND 34

In FIGS. 33 and 34, the conductor housing 150 is O-shaped. A pair of opposed insulation piercing means 152 are provided. It is to be noted that the special insulated conductor 154 is provided with insulation 156 having slots 158 which penetrate nearly to the insulated conductor 154. The slots cooperate with the insulation piercing means 152 for positioning the conductor as illustrated in FIG. 33. FIG. 34 shows the crimping action in which the insulation piercing means 152 penetrate through to the conductor 154 for the purposes of making contact. As previously mentioned, the insulation piercing means 152 may be coated with a conductive material or the housing 150 may itself be conductive. A special conductive metal liner 160 may be inserted as illustrated in FIGS. 33 and 34. The outer portion of the housing may be of nonconductive material.

FIGURE 35

FIG. 35 illustrates a connector housing 162 in which the outer configuration is O-shaped and the inside central cavity 163 is triangular or polygonal shaped. The insulated conductor member 164 has three flat sides when not compressed and has three slots with their vertical axes intersecting the axis of the conductor as illustrated. FIG. 35 shows a central portion illustrating the configuration of the insulated conductor after crimping.

In all instances, the crimping causes the insulation piercing means to penetrate through to the conductor and the slots aid in making this possible. The areas 166 of the central cavity 163 permit the insulation to flow outwardly thereby allowing the insulation piercing means 168 to operate with a minimum of resistance.

FIGURES 36 AND 37

10 In FIG. 36, the insulated conducting member 170 is provided with insulation having a cross or X-configuration. The conductor housing 174 is of O-shaped external configuration and is provided with a central cavity 176 of rectangular or polygonal configuration. The conductor member 170 is provided with slots 178 which cooperate with insulation piercing means 180. It will be obvious that the conducting member 182 illustrated in FIG. 37 may be utilized in FIG. 36 instead of the conducting member 170. The primary difference is that instead of flat portions, the surfaces are rounded. The cross section of the conducting member still has a X or cruciform configuration.

FIGURES 38 AND 39

15 FIG. 38 shows a conductor housing 184 having insulation piercing means 186 which are transverse to the longitudinal axis of the conductor 16.

20 The ribs or insulation piercing means 186 as well as the sides of the housing 184 aid in the positioning of the insulated conductor 16. The sleeve-type housing 184 can be inserted into a triangular opening in an O-shaped sleeve cover housing 188 as illustrated in FIG. 39. A compression ring 190 is used for driving the insulation piercing means 186 into contact with the insulated conductor 16 in the manner heretofore described.

25 It is obvious that the housing 184 may be of sheet metal material or plastic or the like so long as it is of conductive material. It is further obvious that instead of striking out the insulation piercing means, they can be formed in other ways such as by extrusion, etc.

FIGURES 40 AND 41

30 In FIGS. 40 and 41, the sleeve 192 of the conductor C is provided with a conductive coating 194. The insulation piercing means 196 is formed to stop short of the ends of the sleeve 192 as illustrated in FIG. 40. Additional sealing means is provided as at 198 which will flow upon crimping of the crimp rings 200.

35 It is obvious that the open areas provided about the insulated conductors when inserted into the various connectors heretofore described permit for flow of the insulation to allow better penetration of the insulation piercing means upon crimping of the connector.

40 While the invention has been described, it will be understood that it is capable of further modifications, and this application is intended to cover any variations, uses or adaptations of the invention following in general the principles of the invention and including such departures from the present disclosure as come within known or customary practice in the art 45 to which the invention pertains, and as may be applied to the essential features hereinbefore set forth and as fall within the scope of the invention or the limits of the appended claims.

I claim:

- 55 1. A one-piece deformable crimpable nonstrip connector for insulated electrical conductors comprising:
  - a. an elongated tubular conductive housing having conductor encircling deformable crimpable portions
  - b. said encircling portions including top, bottom, side and inside walls
  - c. said inside wall having an insulated conductor-receiving area centrally located and spaced from said top and bottom walls and insulated conductor engaging areas adjacent said top and bottom walls
  - d. said housing in said conductor-engaging areas including integral fixed conduction means extending a substantial

- distance toward said centrally located conductor receiving area from said top and bottom walls respectively and substantially normal to said top and bottom walls
- e. said integral fixed conduction means forming with said inside walls and X-shaped bore
  - f. said conduction means being support means for initially supporting said insulated conductors prior to deformation of said conductor
  - g. said conduction means including integral insulation piercing means for contacting said insulated conductors subsequent to deformation.
2. A one-piece deformable crimpable nonstrip connector for insulated electrical conductors comprising:
- a. an elongated conductive housing having deformable crimpable conductor portions
  - b. said housing having a cross-sectional configuration resembling a pair of E's in face-to-face relation with their bottom legs interconnected and their top legs disconnected and their center legs constituting the insulation piercing means
  - c. the area between said top and bottom legs receiving said electrical conductors, and
  - d. said top and bottom legs being substantially longer than said center leg.
3. A nonstrip connector as in claim 2 and wherein:
- a. said interconnected bottom legs of said E's are joined to form an inverted V.
4. A one-piece deformable crimpable nonstrip connector for insulated electrical conductors comprising:
- a. an elongated conductive housing having deformable crimpable conductor portions
  - b. said housing having a T-shaped cross-sectional configuration with the upright of said T bifurcated to provide a pair of curved legs
  - c. said curved legs providing support means for receiving and holding said electrical conductors, and
  - d. said housing including insulation piercing means on said T's upper portion angled to project toward said curved legs.
5. A nonstrip connector as in claim 4 and wherein:
- a. said piercing means are positioned adjacent the crossbar of said T.
6. A one-piece deformable, crimpable nonstrip connector for insulated electrical conductors comprising:
- a. an elongated tubular conductive housing having conductor encircling deformable, crimping portions
  - b. said encircling portions including top, bottom, side and inside walls
  - c. said inside wall having an insulated conductor receiving area adjacent said top wall and an insulated conductor engaging area adjacent said bottom wall
  - d. said housing in said conductor-engaging area including integral fixed conduction means extending a substantial distance upwardly from said bottom inside wall towards said top inside wall and substantially normal to said top and bottom walls
  - e. said conduction means being support means for initially supporting said insulated conductors prior to deformation of said connector
  - f. said conduction means including integral insulation piercing means for contacting said insulated conductors subsequent to deformation,
  - g. said housing being a sleeve having a D-shaped configura-

tion with said top wall forming the curved portion of said D-shaped configuration.

7. A nonstrip connector as in claim 6 and wherein:
- a. said bottom portion of said D-shaped sleeve supports said fixed conduction means.
  8. A nonstrip connector as in claim 7 and wherein:
  - said insulation piercing means is positioned centrally of said bottom wall.
  9. A nonstrip connector as in claim 7 and wherein:
  - said insulation piercing means includes a series of sets of piercers spaced on the longitudinal axis of said housing.
  10. A nonstrip connector as in claim 9 and wherein:
  - a. said sets of piercers each include at least one pair of piercers.
  11. A nonstrip connector as in claim 7 and wherein:
  - a. said tubular housing includes a cutout portion between the ends thereof.
  12. A nonstrip connector as in claim 7 and wherein:
  - a. said sleeve is plastic, and
  - b. said conduction means having an insulated coating thereon.
  13. A nonstrip connector as in claim 7 and wherein:
  - a. said bottom portion of said D-shaped sleeve includes a divider member positioned centrally of said bottom inside wall.
  14. A nonstrip connector as in claim 7 and wherein:
  - a. said conduction means comprises three spaced projecting-in-line members disposed transversely of the longitudinal axis of said housing.
  15. A nonstrip connector as in claim 7 and wherein:
  - a. said housing includes a plurality of sleeves of D-shaped configuration in abutting relationship.
  16. A one-piece deformable crimpable nonstrip connector for insulated electrical conductors comprising:
    - a. an elongated conductive housing having deformable crimpable conductor portions
    - b. said housing having an E-shaped cross-sectional configuration with the outer legs of said E curved
    - c. said curved legs each having a U-shaped end portion and each forming an area for receiving and supporting said electrical conductors
    - d. the central leg of said E serving as a divider wall for positioning and supporting said electrical conductors, and
    - e. said outer legs having the end of the U-shaped end portions comprising insulation piercing means for said insulated conductors when positioned in said receiving and supporting areas. 17. A nonstrip connector as in claim 16 and wherein:
  - a. said central leg of said E is shorter than said outer legs.
  18. A one-piece deformable crimpable nonstrip connector for insulated electrical conductors comprising:
    - a. an elongated conductive housing having deformable crimpable conductor portions
    - b. said housing having an E-shaped cross-sectional configuration with the legs of said E having curved end portions
    - c. said curved end portions providing support means for receiving and holding said electrical conductors, and
    - d. said housing including insulation piercing means on the center of leg of said E projecting toward the curved end portions of the legs of said E, and
    - e. said center leg of said E being of a height greater than said curved end portions.
